LIFT MECHANISM AFFORDING INDEPENDENT MANUAL ADJUSTMENT AND POWER ACTUA- TION OF SEPARATE TOOLS

August G. Buhr, La Crosse, Wis., assignor to Allis-
Chalmers Manufacturing Company, Milwaukee, Wis.

Application June 29, 1951, Serial No. 234,296

4 Claims. (Cl. 97—46.45)

This invention relates generally to agricultural implements and is more particularly concerned with those features of construction and combination affecting the mounting and adjustment of such implements.

Implements of the type now in general use usually include a plurality of tool frames or rigs operatively mounted in laterally spaced relation beneath and/or adjacent opposite sides of a suitable mobile structure, hereinafter referred to as a tractor. Frequently these frames or groups thereof are supported for relative vertical movement, and in such cases are often provided with dual lift mechanisms operative to effect independent vertical movement or adjustment of the frames or groups. Usually such mechanisms are independently actuated by hand and/or by separate power devices to effect one or more of the following adjustments: simultaneous movement of the frames into and out of working position, selective movement of either frame into and out of working position while the other frame is held in a nonworking position, independent adjustment of working depth, and movement of the frames to the same transport height regardless of differences in depth adjustment.

Attempts have been made to effect these adjustments with mechanisms incorporating a single power device, but in general the constructions heretofore devised have been entirely too complicated and expensive for practical purposes. In addition, these heretofore devised constructions are generally incapable of affording a relative or independent increment adjustment of a plurality of tool rigs, particularly if the power device employed is of the hydraulic ram type.

Accordingly, the present invention is directed toward and has as an object the provision of an implement lift mechanism affording a simplified and inexpensive construction which can be readily actuated by a single power device and is capable of effecting all of the aforementioned adjustments, including a relative or independent increment adjustment of a plurality of rigs.

Another object of this invention is the provision of an implement lift mechanism embodying a simplified combination of parts affording a compact structure requiring a minimum of space for attachment and operation, and which can be readily attached to and removed from a tractor with but little time and effort.

Still another object of the present invention is the provision of a simplified and compact lift mechanism which can be quickly attached to a tractor and operated without interference with rear mounted tools, and which, if desired, may be left on the tractor without materially detracting from the utility of the latter.

A further object of this invention is concerned with the construction of lift mechanism components readily combinable to provide a simplified and compact assembly inherently affording one or more of the aforementioned functions and advantages.

The foregoing and other objects and advantages inherent in an apparatus embodying the present invention will become readily apparent from a consideration of the

2

following disclosure of an illustrative embodiment. And, accordingly, the present invention may be considered as comprising the various features of construction and/or combination hereinafter more particularly pointed out in the detailed description and appended claims, reference being had to the accompanying drawing, in which:

Fig. 1 is a side elevation of a tractor implement combination embodying the invention, the near side rear traction wheel being omitted and other parts being broken away for the sake of clarity;

Fig. 2 is an enlarged section taken on line II—II of Fig. 1 looking in the direction indicated;

Fig. 3 is a plan view of the structure shown in Fig. 2 with both control levers shifted to their forward position in the interest of clarity;

Fig. 4 is an enlarged partial side view showing the control levers of Fig. 1 adjusted to provide the maximum difference in the positions of the lift arms disposed on opposite sides of the tractor as afforded by the pin and slot connection with the actuating ram, parts being broken away for the sake of clarity;

Fig. 5 is a schematic view showing the relative positions of parts when the ground working tools on opposite sides of the tractor are adjusted to afford maximum ground penetration;

Fig. 6 is another schematic view showing the relative repositioning of the parts effected by moving only one of the levers from the position indicated in Fig. 5 to its rearmost position; and

Fig. 7 is a view similar to Fig. 5 which shows the ground working tools on opposite sides of the tractor raised to transport position as effected by a complete expansion of the actuating ram.

Referring particularly to Fig. 1, it will be seen that the tractor element of the combination comprises a rear axle housing 1 having its opposite ends supported in a conventional manner on widely spaced ground engaging rear traction wheels 2, only one of which is shown, a torque tube structure 3 projecting forwardly from a central portion of housing 1 to cylinder block 4, and a front pedestal support 6 conventionally mounting closely spaced dirigible wheels 7. An operator's seat or station 8 is mounted on housing 1 in superimposed spaced relation to a central portion thereof and the steering mechanism includes a rearwardly extending shaft 9 and a steering wheel 11 disposed within easy reach of an operator seated at station 8. In this connection it is to be understood that the tractor is also provided with the usual operator actuated controls, of which only a clutch pedal 12 is shown.

A generally conventional rig mounting structure is detachably carried by the forward portion of the tractor and comprises a frame member 13 which extends transversely across the front of the tractor and has its central portion removably rigidly secured in any known manner to a tractor carried bracket 14. The near end of member 13 is supportingly connected with the outer portion of a transverse draft bar 16 which is rectangular in cross section and has its inner end terminally fixed to a side frame element 17, the latter being detachably fixedly secured to the near side of the tractor in abutting relation thereto. In this connection, it is to be understood that although there are identical rig mounting structures on opposite sides of the tractor, only the one on the near side has been fully shown and described in the interest of simplicity.

A cultivating rig 18 is secured to each draft bar 16 for independent adjustment longitudinally thereof, each rig comprising a rigid front support arm 19 depending from and attached to bar 16 by means of a clamp 21, a gang beam 22 terminating at its forward end in a rigid upstanding part 23, and a pair of parallel links 24 and 26 pivotally uniting vertically spaced portions of arm

19 and upstanding part 23. A plurality of cultivating shovels 27 are suitably attached to beam 22 and each rig may include a plant guard or shield 28 having its forward end pivotally connected to arm 19 by means of a link 25 attached to the pivot support for the forward end of lower link 24, the rear end of this guard being provided with an upstanding part 29 to which is attached a supporting chain 31.

From the foregoing, it should now be obvious that the rigs 18, one on each side of the tractor, are supported for independent transverse adjustment along their respective draft bars 16 and for independent vertical adjustment afforded by the parallel linkages connecting their arms 19 with their upstanding parts 23. And since the particular rig mounting structure and rigs are of no special significance, a more detailed description is believed unnecessary for a full understanding of the present invention.

Referring also to Figs. 2, 3 and 4, an implement lift mechanism for the cultivator rigs is carried by the tractor, preferably in underslung relation to the tractor frame intermediate the ends thereof. This mechanism comprises a fabricated structure including a rigid transverse supporting frame 32, a pair of similar right and left hand control lever assemblies 33 carried by opposite end portions of frame 32, and a lift or rock shaft assembly 34 carried by the aforementioned assemblies.

Frame 32 includes a pair of similar plate members 36 rigidly removably secured to torque tube 3 by bolts 37. Members 36 are formed to extend laterally outward from opposed portions of torque tube 3, with each member presenting vertically depending front and rear marginal flanges 38, of which the corresponding flanges on opposite sides of the tractor are disposed in lateral alignment. A pair of similar plate members 39 are rigidly removably secured to the laterally aligned front and rear flanges 38 by bolts 41. These plates 39 are thus positioned to extend transversely beneath torque tube 3 in vertical parallel relation to one another and laterally outward beyond members 36.

Control lever assemblies 33 each comprise a quadrant type bracket 42 having an opening 43 through a lower portion thereof and having a toothed upper marginal portion 44 generally concentric with opening 43. Opposite marginal portions of brackets 42 are provided with similar inturned flanges 46 rigidly removably secured to opposed end portions of plate members 39 by bolts 47. The brackets 42 are positioned on opposite sides of the tractor in parallel relation longitudinally thereof with their openings 43 disposed in transverse alignment immediately beneath torque tube 3.

A control element or lever 48 is operatively associated with each bracket 42 and comprises an elongated flat bar section having its lower portion rigidly terminally connected in side abutting relation to an upper portion of a plate member 49, the latter having an opening therethrough which is aligned with the opening 43 in the associated bracket 42 and fixedly receives a tubular bearing 51. This bearing is in longitudinal alignment with and extends snugly through the opening 43 on the associated bracket 42, thus affording a fore and aft swinging movement of lever 48 relative to the bracket. Lever 48 is positioned to extend upward alongside the inner face of bracket 42 and is provided with an outwardly offset fixed part 52 having a vertically elongated opening 53 therethrough operatively receiving the lower offset end of a conventional reciprocal latch rod 54. A double gear 56 is rotatably mounted between part 52 and lever 48 with the teeth on the larger gear positioned to receive the lower end of the latch rod therebetween and with the teeth of the smaller gear in mesh with the underlying toothed margin 44 of bracket 42. A more detailed description of the latch mechanism is believed to be unnecessary for a complete understanding of the present invention.

Rock shaft assembly 34 comprises a pair of complementary lift shaft sections 57 and 58 extending outward from the left and right sides of the tractor, respectively, as viewed by a person faced in the normal direction of travel. A first line shaft section 57 includes a tubular sleeve 59 rotatably journaled in the associated bearing 51 and disposed thereby in close adjacent lower relation to torque tube 3, and, a second lift shaft section 58 includes a tubular sleeve 61 similarly journaled in the other bearing 51. Sleeves 59 and 61 extend inwardly from their respective bearings 51 and the opposed end portions thereof are disposed in proximate relation to one another adjacent the right side of the tractor. Round bar elements 62 and 63 extend within and are rigidly united, respectively, with sleeves 59 and 61 for rotation therewith. The laterally outer end portion of sleeve 59 receives the laterally inner end portion of round bar element 62 and the remainder of this sleeve rotatably receives and further supports a portion of round bar element 63 which projects inwardly through and beyond sleeve 61. It will be understood that sections 58 and 57 are coaxially aligned and that sleeve 59 and round bar element 62 may be rotated relative to sleeve 61 and round bar element 63. Round bar elements 62 and 63 extend laterally outward beyond their respective bearings 51 and then forward generally at a right angle to their common transverse axis, these elements terminating in outwardly projecting similar left and right side implement lift portions 66 disposed in generally parallel relation to said axis. Similar angle section extensions 67 are rigidly removably secured in any suitable manner to lift portions 66, these extensions projecting transversely outward over the gang beams 22 associated therewith. Each gang beam 22 is operatively connected with the associated lift extension 67 by means of a chain or the like 68, the rear ends of the plant guards being also connected to these lift extensions by the aforementioned chains 31.

First lift shaft section 57 has an implement lift portion 40 at one side of the tractor, the left side, and presents an actuating arm 69 at the other side of the tractor. Second lift shaft section 58 has an implement lift portion 45 at the other side of the tractor, the right side, and presents an actuating arm 71 at this other side. Actuating arms 69 and 71 are similar to each other and are terminally rigidly secured, as by welding, respectively to the end portion of sleeve 59 opposing sleeve 61 and to a portion of sleeve 61 intermediate the ends thereof, being normally disposed thereby to extend radially rearward and downward therefrom in transverse alignment. 50 Lower opposed portions of arms 69 and 71 are provided with transversely aligned arcuate openings 72 therethrough which are concentric with the longitudinal axis of shaft 34. A pair of similar stop arms 73 and 74 are terminally 55 rigidly secured, as by welding, respectively to sleeves 59 and 61 and are normally disposed to extend radially rearward and upward therefrom in transverse alignment and adjacent the laterally inner ends of bearings 51 for engagement with the inwardly extending stop projection 60 76 on the associated lever 48.

Any suitable power actuating device, such as a single 65 acting hydraulic ram 77, is pivotally mounted on rear axle structure 1 to extend forward therefrom in general alignment with the space between actuating arms 69 and 71. Ram 77 includes a conventional plunger 78 which presents an exposed forward end portion when the ram is completely collapsed. The forward end of plunger 78 is operatively connected with the rear end of an extension bar 79 having its forward end disposed between and connected with arms 69 and 71 by means of an oppositely projecting pin 81 passing through the arcuate openings or slots 72. It will be evident, therefore, that the slots 72 and the pin 81 on extension 79 provide a lost motion connection between arms 69 and 71 and the ram 75 77. Ram 77 receives fluid under pressure from a suit-

able pump 82 through a connecting conduit 83, the flow of fluid to and from the ram being controlled in a conventional manner by selectively moving a lever 84 to a position effecting the desired result.

If desired, the tractor may be provided with a rear attached ground working or other implement, indicated generally by numeral 86. As illustrated, this rear attached implement is mounted for vertical adjustment by means of conventional draft links 87 and lift arms 88, the latter being operatively connected with a power device shown generally as the plunger 89 of a single acting ram 91. Pump 82 supplies ram 91 with fluid under pressure through a connecting conduit 92, the flow of fluid to and from this ram being also controlled, in the conventional manner previously indicated with respect to ram 77, by the actuation of lever 84. In this connection, it should be understood that the rams 77 and 91 may be simultaneously expanded or contracted, as desired, by the selective actuation of lever 84, and that the particular means employed for effecting such a control or operation is in no manner essential for a complete understanding of the present invention. Consequently, a further description of such mechanism has been dispensed with as being unnecessary.

When the ground working tools on opposite sides of the tractor are adjusted to afford maximum ground penetration (refer to Fig. 5), control levers 48 are disposed in their extreme forward portions relative to the toothed portion 44 of bracket 42 and the hydraulic ram 77 is in its fully retracted position. In order to simultaneously elevate the rigs on opposite sides of the tractor to transport position (refer to Fig. 7), the operator seated at station 8 moves lever 84 to a position such that pump 82 delivers fluid under pressure to ram 77, whereupon plunger 78 moves forward to its fully extended position. This results in a forward movement of extension 79 and pin 81, which in turn causes a limited rocking movement, clockwise as viewed in Fig. 1, of shaft sections 57 and 58 about their common transverse axis. Consequently, stop arms 73 and 74 swing forward freely away from stops 76, and lift portions 66 swing upward and elevate the rigs 18 by means of the connecting lift chains 68. When only simultaneous movement of the rigs on opposite sides of the tractor is contemplated, shaft sections 57 and 58 may be united for rocking movement as a unit by inserting a removable bolt means (not shown) through the pair of transversely aligned openings 93 provided in arms 69 and 71 intermediate the ends thereof. The movement of the rigs to transport position as just described is readily effected without shifting or adjusting the positions of levers 48, simply by fully expanding ram 77.

Most hydraulic controls of the type herein indicated enable the operator to partially expand or contract the ram or rams simply by placing the control lever in a neutral or intermediate position, commonly called "hold position," terminating the admission or withdrawal of additional fluid. However, it is extremely difficult, if not impossible, to quickly manipulate the control lever to effect increment adjustment as to the extent of soil penetration by the rig carried tools. Moreover, the valve mechanisms necessarily incorporated in such controls are subject to leakage which also makes it difficult to retain the implements in a selected position. In addition, the use of a single power actuating device usually precludes effecting a relative or independent increment adjustment of a plurality of tool rigs. These difficulties are entirely overcome and the desired control effected simply by the provision of a lift mechanism embodying parts constructed and combined for coaction as hereinbefore described. This phase of the operation is quite simple and can be readily effected with a minimum of effort.

For example, assuming the tool rigs are in their transport position shown in Fig. 7, the first step is to move

both levers 48 to their extreme rearward position relative to the toothed portion 44 of bracket 42. This can be done with but little effort as such movement of these levers fails to bring the stops 76 thereon into engagement with arms 73 and 74. When this has been done, a movement of control lever 84 to a position permitting flow of fluid from or out of ram 77 enables the weight of the raised implements to effect a collapse or contraction of the ram to an extent determined by the engagement of arms 73 and 74 with the stop 76 on the associated lever 48. This places the cultivating shovels of both rigs 18 slightly above the ground generally in the position shown for the uppermost shovel in Fig. 6. Under these conditions, either rig may be further lowered relative to the other an extent limited by the effective length of the arcuate opening 72 in the associated actuating arm, i. e. arm 69 or 71. The limit of this relative lowering movement is clearly shown in Fig. 6 by the vertical spacing of the shovels 27 and the angular displacement of lift arm portions 62 and 63. Obviously, the rearmost lever 48 can now be independently moved to its foremost limiting position relative to its toothed quadrant position 44, that is, to the position shown in Fig. 5 which places the shovels on the associated rig in their lowermost position. Alternatively, any movement of the rearmost control lever toward its foremost position permits a corresponding relative forward movement of the other lever, i. e. a relative lowering movement of the shovels controlled thereby.

In this connection, the use of a double gear latch mechanism embodying gear elements having a difference in diameters of the order shown affords a relative or simultaneous increment adjustment of the tool rigs 18 with a minimum movement of levers 48 and with a toothed quadrant of practical size. Moreover, once the stop arms 73 and 74 are engaged with the stops 76 on the associated levers 48, the latter may be moved separately or together toward their rearmost limiting positions to effect either a relative or simultaneous raising of the tool rigs. Of course, the extent of relative raising movement is limited by the effective length of the arcuate slots 72 as previously mentioned with respect to a relative lowering of the rigs. In addition, when the rigs are in a lowered position such that the rearmost lever 48 is forward of its rearward limit, a further rearward actuation of this lever will effect a raising movement of both rigs providing the forward angular displacement of the other lever is such (note Fig. 4) that pin 81 engages the rear end of the slot 72 in arm 71 and the forward end of the slot 72 in arm 69 before the actuated lever reaches its rearmost position. Of course, such a simultaneous raising of both rigs effects an expansion of ram 77, which produces a resisting vacuum within the ram cylinder that must be overcome by the force manually applied to the actuating lever 48.

Consequently, with the parts positioned as shown in Fig. 5, either lever 48 may be manually moved to its extreme rearward position which will first effect a relative raising of the associated rig followed by a simultaneous movement of the arms 69, 71 and both rigs to the relative positions indicated in Fig. 6. During this movement, the nonactuated lever will remain in its foremost position by reason of the engagement of its latch element 54 with the associated double gear 56. Obviously, the actuating lever will effect the same relative movement and a lesser extent of simultaneous movement if it is shifted from its position shown in Fig. 5 to some position intermediate the angular displacement of the levers shown in Fig. 6. Similarly, the extent of the initial relative movement depends upon the relative angular displacement of the levers 48, i. e. there would be no initial relative movement with the maximum angular displacement of the levers shown in Fig. 4 and a maximum initial relative movement with no angular displacement as shown in Fig. 5.

Furthermore, regardless of the positions of the levers 48, a movement of control lever 84 to its ram expanding position, results in a simultaneous movement of both rigs to the same height, that is, to the transport position shown in Fig. 7. As previously indicated, an angular displacement of the levers 48 will also result in an initial movement of one rig relative to the other. Consequently, it should now be apparent that in addition to using the ram control lever 84 for effecting a movement of both rigs to their transport position, this lever is also actuated to effect a lowering movement of both rigs to the same or different positions of elevation as determined by the setting of lift levers 48. Also, when thus lowered, levers 48 may be simultaneously or independently actuated to effect increment vertical adjustment of one or both rigs, and therefore the depth of soil penetration, as desired. In this connection, it should also be apparent that the extent to which the rigs and plant guards can be raised or lowered by the actuation of levers 48 may be further varied by changing the effective length of the lift chains 68 and 31. For example, with the tool rigs and shields resting on top of the ground, these chains can be disconnected, the levers 48 shifted to either raise or lower the lift arms 66 relative to the rigs and guards, and the chains reconnected.

If desired, the implement may be readily removed from the tractor in the usual manner and without materially affecting the lift mechanism, simply by first lowering the implement to the ground and then removing the lift arm extensions 67 to which the chains 31 and 68 are connected. This leaves the lift mechanism substantially intact, and the mounting and compactness of the latter permits the tractor to be effectively and efficiently used on other jobs, as desired. Moreover, this lift mechanism in no manner hinders or interferes with the mounting and operation of rear attached tools or other apparatus supported on or coupled to the rear of the tractor. Neither does this lift mechanism present any obstruction to the visibility of an operator seated at station 8.

In the event it is desired to also remove the lift mechanism from the tractor, this can be readily done, assuming the implement has already been removed as described, simply by disconnecting extension 79 from ram plunger 78, and then removing the studs 37 securing frame members 36 to torque tube 3, whereupon the entire lift mechanism may be lowered to the ground. If both the implement and lift mechanism are to be removed at the same time, lift arm extensions 67 need not be removed from the portions 66, as all that is necessary is to separate the implement from the lift mechanism by disconnecting the chains 31 and 68. Obviously, the lift mechanism may be just as readily reattached to the tractor simply by reversing the procedure described for detaching.

In view of the foregoing, it should now be obvious that a lift mechanism constructed and mounted in accordance with the teachings herein disclosed is inherently capable of affording the improved results and advantages previously mentioned or discussed. Also, it should be apparent that the mechanism disclosed is applicable to tractors other than those of the torque tube type. Consequently, it is to be understood that it is not intended to limit the invention to exact details of construction, mounting, and combination herein shown and described for purposes of illustration, as various modifications within the scope of the appended claims may occur to persons skilled in the art.

It is claimed and desired to secure by Letters Patent:

1. A lift mechanism comprising a pair of supports adapted to be fixedly secured to a mobile frame structure in spaced transverse relation to the direction of travel, a bearing structure mounted in each support for rotation relative thereto, a rock shaft section journaled in each bearing structure, said sections having coaxially joined portions affording a relative rotation of said sections, a control lever actuably connected with the associated bear-

ing structure for adjustably turning the latter relative to its associated bearing support and relative to the shaft section supported thereby, said supports each presenting an arcuate gear segment disposed in spaced concentric relation with respect to the axis of rotation of said shaft sections, a double gear carried by each lever for rotation relative thereto and presenting a toothed periphery adjacent said lever in mesh with said arcuate segment of the associated support and a toothed periphery of larger diameter disposed in partially overlapping relation to the side of the support remote from the associated lever, a reciprocable element carried by said lever in position for selective latching engagement with said toothed periphery of larger diameter, said shaft sections each presenting a radially offset lift portion, radially extending actuating arms disposed in proximate side opposed relation to each other on said shaft sections, respectively, a stop projection secured to each shaft section and angularly spaced from its associated actuating arm and disposed adjacent the associated control lever, a stop element carried by each control lever and positioned thereby for engagement with the stop projection on the associated shaft section, and a removable means uniting said actuating arms for simultaneous movement, said actuating arms having transversely aligned arcuate slots adapted for connection with an actuating device and being operative when said arms are united to afford a limited movement of said actuating arms relative to said device, and operative, when said arm uniting means is removed, to also afford a limited movement of said arms relative to each other.

2. An agricultural machine comprising, in combination: a tractor having a rearward operator's station, a pair of implement frames mounted at opposite sides of said tractor forwardly of said operator's station for adjustment independently of each other between implement raised and implement lowered positions, a bracket structure mounted on said tractor forwardly of said operator's station, a first lift shaft section rotatably supported in said bracket structure on an axis extending transversely of said tractor and having an implement lift portion operatively connected with one of said implement frames at one side of said tractor, and presenting an actuating arm at the other side of said tractor; a second lift shaft section rotatably supported in said bracket structure coaxially with said first lift shaft section and having an actuating arm at said other side of said tractor and presenting an implement lift portion operatively connected with the other of said implement frames at said other side of said tractor; said actuating arms extending radially from said lift shaft sections in proximity to each other at said other side of said tractor; a pair of relatively rotatable control elements pivotally mounted, respectively, on said lift shaft sections, each of said lift shaft sections and its associated control element presenting adjacent portions coactable with each other to selectively determine limit positions to which said lift shaft sections can be rotated relative to their associated control elements in implement lowering direction, and a single actuating device connected with said actuating arms at said other side of said tractor and operative to rotate said lift shaft sections in implement raising direction and permitting limited rotation of each of said lift shaft sections relative to each other in implement lowering direction.

3. An agricultural implement as set forth in claim 2, and further comprising tubular bearing elements rigidly secured, respectively, to said control elements and rotatably connected in supporting relation, respectively, with said lift shaft sections, and means rotatably mounting said bearing elements on said bracket structure.

4. An agricultural implement as set forth in claim 2, in which said coactable adjacent portions of each of said lift shaft sections and its associated control element comprises a stop projection extending radially from said lift

shaft section and a stop element extending from said control element in a direction longitudinally of said lift shaft section.
